J. Stewart
Threshing Mach.
Patented Nov. 17, 1834.

Mar. 17, 1834

John Stewart, Cambridge, Mass.

Seth's Patent

6468

The subject is referred to in the Letter Patent and making part of the same containing a description in the words of the said John Stewart himself of his Improvement in the Threshing Machine and Straw-Cutter.

To all whom these presents shall come, be it known that John Stewart, of the town of Cambridge in the County of Worcester and State of Massa. Co. have invented a new and useful Improvement in the Machine for Threshing grain and cutting straw, and that the following is a full and exact description thereof:-

To make a Threshing Machine of the usual construction, first, it is to be noted that the side of the frame which has the whole weight of the Threshing Cylinder is made double to receive a set of wheels which are intended to give the velocity required to the Threshing Cylinder - these wheels are made as follows - at the top of the frame and at the opposite side of the Threshing Cylinder is an axletree which is a band wheel of about five feet diameter - a wheel which receives the band from the top of the band axletree to be hereafter mentioned and a small cog-wheel of eight teeth the mentioned wheel gives motion to the Straw-Cutter to be hereafter mentioned immediately below this axis is another similar to it on which is a small wheel that receives its motion from the band wheel above described and on the side of it a band wheel of five feet diameter which gives the motion to the straw-cutter on the end of the Threshing Machine.

At some distance from the Threshing machine is another frame in which works a horizontal band wheel of six or twelve feet diameter to be propelled by horse or other animal power. A band from this wheel passes around all wheels as above described. The straw-cutter consists of a frame and wheel which is as long as the width of the Threshing Machine.

The one end turns a small cog-wheel which receives its motion from the wheel as before mentioned and on the other end are attached two cutting knives on the side of the frame is a feeding box in all other

Nov. 17, 1834

from a set of four steel blades & corresponds with the Cutters, all the 24
of the blades work in circles and any of them can be removed from the
machine at pleasure the machine is operated in the following manner. At
first the equal power is attached to the beam in the shaft of the horizon-
tal wheel and as it works by means of the vibration of hand wheel the
whole wheel is put in motion. The Threshing machine and straw cutter
are intended to work at the same time. Then the Threshing Machine
will be set the steel-blades removed and while the straw Cutters operate
in front of the Threshing Machine must be taken off also the
straw cutter the Threshing Cylinders I do not claim to be the inventors of the
threshing machine or straw cutter as both are public property but when
I invented the vicinity of and for which last Sister's Patent is the
invention of the machine the machine and the general arrangement of
the parts as above described.

Witnessing that the above is a full and exact description
of my invention I have hereunto subscribed my Name this 14 day of

November 1834
